DESIGN.

—o—

E. MANKEY.

OPEN WORK PANEL.

No. 16,428.

Patented Dec. 29, 1885.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,428, dated December 29, 1885.

Application filed November 13, 1885. Serial No. 182,760. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

Upon the face of the panel appear rectangular elevations A, arranged in rows, as 1 and 2, the elevations in each row being separated by channels B, and the several rows being separated by channels C. The upper edges of said elevations are beveled or inclined. In the center of each elevation, and extending through the panel, is an opening, D. Each opening is of hexagonal form, the said hexagon having

two straight sides, E E', parallel and opposite, and four curved sides, F G H I. The sides F G are inwardly convex, and are between the ends of the sides E E'. The sides H I extend between the opposite ends of the sides E E', and are opposite the sides F G.

I claim—

The design for an open-work panel herein shown and described, which consists in the quadrangular elevations A, arranged in rows, with intermediate channels, B C, and the openings D through said elevations, the said openings each having six sides, E E' F G H I.

FREDERICK MANKEY.
